United States Patent Office

Des. 193,510
Patented Sept. 4, 1962

193,510

CLOTHESPIN

Morris R. Sanders, Lansdowne, Pa., assignor to Doo-Dee Pins, Inc., Lansdowne, Pa., a corporation of New Jersey

Filed July 5, 1961, Ser. No. 65,810

Term of patent 14 years

(Cl. D17—6)

Fig. 1

Fig. 2

Fig. 3

Fig. 4

FIG. 1 is a perspective view of a clothespin showing my new design;

FIG. 2 is an enlarged front elevational view thereof, it being understood that the lateral edges are toothed through the extent indicated by the dot-dash lines as shown;

FIG. 3 is a rear elevational view of the same; and FIG. 4 is a side elevational view of the same.

I claim:

The ornamental design for a clothespin, as shown and described.
